INFANT'S TOILET SEAT

Clarence W. Steele and David I. Levine, Gardner, Mass., assignors to Heywood-Wakefield Company, Boston, Mass., a corporation of Massachusetts

Application January 16, 1933, Serial No. 651,869

7 Claims. (Cl. 4—239)

The present invention relates to an infant's toilet seat, and particularly to a structure of this character which is readily detachable to, or removable from, the conventional toilet seat.

5 The principal feature of the invention resides in a toilet device which is secured in position on the usual adult's toilet seat by movement of the back portion of the device into raised position, the seat portion being preferably secured to the 10 usual or conventional seat by engagement with the opposite sides thereof, thereby accommodating itself to the various types of toilet seats. The objects and further advantages of the invention will appear from the following detailed description 15 taken in connection with the accompanying drawing in which:—

Fig. 1 is a side view in elevation of an infant's toilet device embodying the invention.

Fig. 2 is an enlarged fragmentary elevation of 20 the pivotal connection between the back and the seat portions of the device.

Fig. 3 is a vertical section along the line 3—3 of Fig. 1.

Fig. 4 is a fragmentary vertical section along 25 the line 4—4 of Fig. 1.

Like reference characters refer to like parts in the different figures.

Referring to the drawing, the device comprises a seat portion 1 of the usual form having an opening 2 therein, and a back portion 3 pivotally mounted adjacent the back of the seat portion and arranged to extend upwardly substantially at right angles to the seat portion or, when in folded relation, adjacent and substantially parallel to the seat portion. Arms 4 are pivotally mounted on the back portion 3 on opposite sides thereof and project forwardly in parallel relation to the seat portion 1 to support the child on the seat. Each of said arms is supported at the forward end in spaced relation to the seat portion by a link 5, the upper end of which is received in an opening 6 in the side of the arm for pivotal movement thereon. The lower end of the link projects into and is pivotally mounted in a horizontal opening 7 in the side of the seat portion.

The back portion 2 is resiliently supported in the raised position shown in Fig. 1 by a clip 8 secured to the side of the seat portion as by screws 10 and provided with a vertically arranged notch 11 which engages the link 5 when the latter is in the substantially vertical position shown. The clip is resilient and permits folding of the device by a forward pressure on the back portion to move the device forwardly, said clip yielding to 55 permit the link 5 to move out of the notch 11

therein, although supporting said back against accidental folding or forward movement.

The pivotal connection of the back portion 3 to the seat portion is best shown in Fig. 2. Referring to this figure, an angular lever 12 is secured at one end to each lower corner of the back portion as by screws 13 and the free end of said lever extends forwardly and is pivotally mounted on a screw 14 in the side of the seat portion 2. By this arrangement of the lever, movement of the back portion rearwardly is limited by engagement of the lower edge 15 of said back portion with the upper surface of the seat portion, without the provision of additional stops, and said back portion is readily folded forwardly about 15 the pivotal screws 14.

As best shown in Fig. 3, the under side of the seat portion 1 is provided with opposed depending hooks 16 and 17 which are adapted to engage opposite sides of the permanent or adult's toilet seat 18 for securing the infant's seat thereto. These hooks, as will be apparent, engage the permanent seat and secure the infant's toilet seat against sliding movement thereon as well as against removal from said adult's seat. The securing action is aided by rubber knobs 20 on the under side of the seat at opposite ends thereof which engage the upper surface of the adult's seat.

The depending hooks 16 and 17 which are preferably rubber covered, as shown, are formed on the forward ends of rods 21 pivotally mounted on the under side of the seat portion in brackets 22 secured to said seat portion. The rearward portions 23 of said rods beyond the brackets are bent to extend upwardly and outwardly in notches 24 provided in the seat portion forwardly of the pivotal screws 14. The outer end of each rod engages a slot 25 in an arm 26 pivotally mounted at the end remote from the slot on the screw 14 and beneath the lever 12. Each arm 26 is provided with an outwardly projecting lug 27 for engagement with the lower horizontal edge 28 of the lever 12 for movement of said arm by said lever as the back portion 2 is moved into the raised position shown, thereby elevating the ends 23 of the rod and procuring movement of the hooks 16 and 17 away from each other and into locking engagement with the adult's seat. Each arm 26 is also provided with a second outwardly projecting lug 30 in a position to engage the upper edge 31 of the lever 12 as the back portion 2 is moved into the folded position, this movement of the back portion 2 procuring movement of the securing hooks toward each other to release the 55

infant's seat. It will be noted that the lugs 27 and 30 are positioned so that the securing hooks are moved into operative engagement with the adult's seat as the back portion 2 approaches the end of its movement into raised position, and similarly the securing hooks are withdrawn from operative engagement as the back portion 2 approaches the end of its movement into folded position. In this way the device is not immediately released from the adult's seat by a slight forward movement of the back portion; in fact, the device cannot be removed from the adult's seat until the back portion is moved into substantially parallel relation to the seat portion.

15. From the foregoing, it will be apparent that the infant's seat is locked on the permanent adult's seat by movement of the back portion into raised position, the locking occurring as the back approaches the end of its movement in this direction. The back portion is resiliently maintained in raised position to prevent accidental release of the securing members, which are released by folding movement of the back portion into parallel relation to the seat portion, said securing members being released as the back portion approaches the end of its movement into folded position. Release of the infant's seat, from the permanent seat is thus impossible while a child is positioned on the seat, even though the back portion 3 be moved part of the distance into folded position.

We claim,

1. In an infant's toilet seat, the combination with a seat, and a back pivotally mounted on said seat for movement relative thereto, of opposed securing members for engagement with a support on which the seat is positioned, means operable by movement of said back relative to the seat in one direction for positive movement of said securing members into operative securing position and operable by movement of said back in the opposite direction for positive movement of said securing members into released position, and a lost-motion connection between said members and the back to provide for motion of the securing members during a portion only of the movement of the back and as the latter approaches the end of its movement in either direction.

2. In an infant's toilet seat, the combination with a seat, and a back pivotally mounted on said seat for movement relative thereto, said back having a limited movement in either direction, of opposed securing members for engagement with a support on which the seat is positioned, and means operable by movement of the back as it approaches the limit of movement in either direction for positively actuating said securing members into or out of operative securing position.

3. In an infant's toilet seat, the combination with a seat, and a back pivotally mounted on said seat for movement relative thereto, said back, at the end of its movement into folded po-

sition, extending substantially parallel to the seat, of opposed securing members for engagement with a support on which the seat is positioned, and means responsive to movement of said back as the latter approaches the end of its movement into folded position for positive movement of said securing members into inoperative position.

4. In an infant's toilet seat, the combination with a seat, and a back pivotally mounted on said seat for movement relative thereto into and out of folded position, of opposed securing members for engagement with opposite sides of a support on which the seat is positioned, said securing members being pivotally supported on said seat on axes perpendicular to the pivotal axis of the back, and means operable by movement of the back relative to the seat in opposite directions for positively actuating said members into and out of operative position.

5. In an infant's toilet seat, the combination with a seat, and a back pivotally mounted on said seat for movement relative thereto into and out of folded position, of opposed securing members for engagement with opposite sides of a support on which the seat is positioned, said securing members being pivotally supported on said seat on axes perpendicular to the pivotal axis of the back, means operable by movement of said back relative to the seat for positively actuating said members into and out of operative position, and a lost-motion connection between said securing members and the back to provide for motion of the securing members during a portion only of the movement of the back and as the latter approaches the end of its movement in either direction.

6. In an infant's toilet seat, the combination with a seat and a back pivotally mounted on said seat for movement relative thereto, said back having a limited movement in either direction, of a securing member for engagement with a support on which the seat is positioned, and means operable by movement of the back as it approaches the limit of movement in either direction for positively actuating said securing member into and out of operative securing position.

7. In an infant's toilet seat, the combination with a seat and a back pivotally mounted on said seat for movement relative thereto, said back at the end of its movement into folded position extending substantially parallel to the seat, of a securing member for engagement with a support on which the seat is positioned, and means responsive to movement of said back as the latter approaches the end of its movement into folded position for positive movement of said securing member into operative position.
